UNITED STATES PATENT OFFICE.

HUBERT J. HOPKINS, OF SAN FRANCISCO, CALIFORNIA.

LADDER-RAISING DEVICE.

1,394,498.

Specification of Letters Patent.

Patented Oct. 18, 1921.

Application filed February 18, 1920. Serial No. 359,604.

To all whom it may concern:

Be it known that I, HUBERT J. HOPKINS, a citizen of the United States, residing at the city and county of San Francisco and

5 State of California, have invented a new and useful Improvement in Ladder-Raising Devices, of which the following is a specification.

This invention relates to extension ladders 10 such as employed by fire departments and the like and especially to a raising device to be employed in conjunction with the same.

One of the objects of the present invention 15 is to provide a simple substantial rigid ladder of the extension type such as employed by fire departments and the like and especially to provide means for facilitating the extension and raising of the same.

Another object of the invention is to provide 20 a carriage which is pivotally attached to the lower end of the ladder, said carriage serving two main functions; first that of temporarily supporting the ladder when removed from the truck carrying the same, 25 and second that of a support about which the ladder may be swung to an approximate vertical position before it is extended and raised into position against a building or the like.

30 Another object of the invention is to form a telescopic connection between the carriage and the ladder which is operable independent of the pivotal connection and which automatically renders the carriage inoperable when the ladder assumes a vertical 35 position.

Another object of the invention is to provide 40 a collapsible truss whereby the main ladder and the extension are rigidly braced when in an extended position.

Further objects will hereinafter appear.

The invention consists of the parts and the construction, combination and arrangement of parts as hereinafter more fully described and claimed, having reference to the 45 accompanying drawings, in which—

Figure 1 is a side elevation of the ladder showing it extended and in position for use.

Fig. 2 is a cross section on line 2—2 of 50 Fig. 3.

Fig. 3 is a side elevation of the section taken on line 3—3 of Fig. 2.

Fig. 4 is a detail view of the foot brace lock.

55 Figs. 5 and 6 are detail views of the ratchet wheels and pawls used in conjunc-

tion with the ladder retaining and ladder extending mechanism.

Fig. 7 is an end elevation of the ladder showing the hand crank whereby the extension on the ladder is operated.

Fig. 8 is a plan view of the same.

Fig. 9 is an enlarged view in side elevation of the lower end of the ladder showing it supported in a horizontal position, 65 and its tilted position in dotted lines.

Fig. 10 is a detail view of the foot brace.

Fig. 11 is a detail view of the ladder supporting standards.

Fig. 12 is a detail view of the lateral 70 braces employed in conjunction with the standards shown in Fig. 11.

Fig. 13 is a detail view in side elevation showing the ladder assuming a vertical position.

75 Fig. 14 is an enlarged detail sectional view of the telescope mechanism employed in conjunction with the standards in Figs. 9 and 11.

Fig. 15 is a detail view of the securing 80 means employed in connection with the standards shown in Fig. 11.

Fig. 16 is a plan view in section of the lifting pole lock taken on line 16—16 of Fig. 20.

85 Fig. 17 is a side elevation of the keeper for supporting one end of the lifting pole when out in use.

Fig. 18 is a cross section on line 18—18 of Fig. 17.

90 Fig. 19 is a cross section on line 19—19 of Fig. 20.

Fig. 20 is a side elevation of Fig. 16.

Fig. 21 is a detail view showing the locking up wedges employed to move a ladder 95 across a sidewalk curb or other obstruction.

Referring to the drawings in detail, A indicates the main or lower end of a ladder and 2 an extensible section which may be telescoped or extended with relation to the 100 main section A. The ladder here shown is particularly adapted for fire service and the like, and one of the main features of the present invention is to provide means for facilitating the raising and extending of 105 the ladder, and further to provide means for rigidly bracing the extensible section with relation to the main section when the ladder as a whole is extended and raised into position.

Referring to Figs. 1 and 9, it will be seen that the ladder as a whole is adapted to

be supported at one end by means of a carriage B. This carriage is pivotally attached to the ladder as at 3, and it serves two main functions, first that of supporting 5 one end of the ladder when it assumes a horizontal position, such as shown in Fig. 9, and secondly that of a support about which the ladder may be swung into an approximate vertical position as indicated 10 by dotted lines in Fig. 9 and by full lines in Fig. 1.

The carriage proper consists of frame sections 4 and 5, which are rigidly connected by cross braces 6 and a shaft 7. Journalized 15 on the shaft and adapted to support the carriage are a pair of wheels 8, and slidably mounted in guide plates 9, secured on each frame section 4, are auxiliary bracing and locking legs 10. These legs assume the full 20 line position shown in Fig. 9 when the carriage is employed, but are otherwise raised into the dotted line position indicated at 10°. Each guide for the legs 10 consists of a pair 25 of interspaced plates 9, between which the legs are slidably mounted. The upper ends of the legs are offset as at 11, and the frame sections 4 and 5 are notched as at 12' to receive the offset sections of the legs and to secure the same against upward movement 30 when in an extended position. The legs 10 when lowered are otherwise connected by a detachable chain 12 to prevent spreading of the same and they are secured in the raised position indicated by the dotted lines at 10° by means of pins 13, which pass through perforations 14 formed in the plate 15, and the upper ends of the legs proper as at 14'. The carriage may be locked in vertical position, 35 first by extending the legs 10, and secondly by means of an endless cable and chain 16. The cable section 16 passes over a pulley 17, while the chain section 18 passes over a sprocket wheel 19. The sprocket wheel is journaled at the lowermost end of the ladder and is provided with a ratchet wheel and 40 pawl such as shown at 20 and 20' respectively, to lock the chain and cable against movement consequently the carriage with the ladder assumes a horizontal position. 45 This position is assumed immediately after the ladder is removed from the truck carrying the same and the sprocket wheel 19 is only released to permit the ladder to be freely turned when the pawl 20' is disconnected from the ratchet wheel 20 or when it 50 is desired to tip the ladder about the carriage and swing into the dotted line position shown in Fig. 9. This is of course only done when the ladder is in an approximate position with relation to the building or other object against which it is going to be raised. 55

There are two pair of legs 10; one pair for each frame section 4 and 5. There are similarly two chain and cable sections 18 60 and 16 and two sprocket wheels 19 with re-

spective coöperating pawls 20' and ratchets 20, that is one set is arranged on each side of the ladder to positively secure the carriage B in vertical position when supporting the ladder and when raising the same. The only 70 time that the pawl 20' is released is when the ladder is tilted or swung about the pivotal connection 3.

To materially facilitate the raising of the ladder or swinging of the same about the 75 pivotal connection 3, I provide a foot brace frame 21 and an auxiliary foot brace 22. The frame 21 is pivotally attached to the lower end of the ladder as at 23 and it is held in an extended position by means of 80 a pair of links 24, one being pivotally connected to each side thereof. These links are furthermore pivotally attached at their upper ends to sliding blocks 25 which straddle the guide rods 26 and it is therefore possible 85 to fold the foot brace 21 over against the ladder as shown in Fig. 1, whenever desired, and similarly the auxiliary foot brace 22 as this is pivotally attached to the frame 21 and is connected thereto by means of a chain 90 95 27, the frames 21 and 22 being provided with rungs such as shown at 28 in Fig. 10, which register with or may entirely displace rungs on the lower end of the ladder. The foot braces or frames 21 and 22 are employed when the ladder is tilted about the pivotal connection 3 on the carriage B as they provide an ideal means for handling that end of the ladder, and they also materially increase the leverage presented, thereby decreasing 100 the number of men required when raising or lowering the ladder. The foot braces are of course folded up against the ladder when it is raised, and they are therefore only useful during the raising operation. 105

With the ladder tilted or swung in the position shown in Fig. 1, it is possible to temporarily support it by means of a pair of poles 29, said poles being also employed when raising the ladder into its final vertical position. The poles are universally connected with the lower section of the ladder so that the fireman may assume any convenient position when employing the same. The universal connection employed is shown 110 115 in Figs. 1, 16, 19 and 20. The connection consists of a bracket 30, which is pivotally attached to the ladder by means of a bolt 31. The bracket 30 supports a second bracket 32, which is pivotally attached to the bracket 120 30, by means of a bolt 33 and as the bolts 31 and 33 are mounted at right angles to each other, it can readily be seen that if the pole is attached thereto, universal movement of the same will be permitted. The 125 bracket 32 carries a pair of sheave-like rollers 34, between which the pole 29 passes. A pair of collars 35, secured on one end of the pole however engage with the sheaves 34, when the pole is extended, and thereby 130

prevent the pole from passing between the same. If the pole is pulled along the ladder until the collars 35 engage the sheaves, it happens that the pole becomes locked 5 against endwise movement with relation to the sheaves and the brackets 30 and 32. This is accomplished by means of a latch 36 which is pivotally mounted in the pole as at 37 and projected automatically by means of 10 a spring 38 when the pole's extended position is assumed, that is, latch 36 engages one side of the bracket 32 and thus locks the pole against endwise movement in one direction, while engagement of the collars 35 with the 15 sheaves locks the pole against endwise movement in the opposite direction. The universal connection of the brackets 30 and 32, however permits universal movement of the free end of the pole. The ladder is also 20 provided with a pair of fork-shaped brackets 39. These are placed at the lower end of the ladder and are provided for the reception of the collars 35. This position of the pole in parallelism with the main section 25 of the ladder, as shown by dotted lines in Fig. 1, is only assumed when the poles are not in use, and this position can only be assumed when the latch 36 is released and the pole is pushed upwardly through the 30 sheaves 34 to such an extent that when swung into parallelism with the ladder, the collars 35 will be received by the fork-shaped bracket 39. There are two poles such as shown, one on each side of the 35 ladder. Both are similarly constructed and a description of one should therefore suffice.

Another important feature of the invention is the provision of means for raising the extension section of the ladder when the 40 main ladder has been tilted into the position shown in Fig. 1. The extension ladder is telescopic with relation to the main ladder, it being slidably supported between the main side sections of ladder A as shown in 45 Fig. 2. Raising of the extension is accomplished by means of a pair of pulleys 43 and hand cranks 41. The extension ladder may be locked in any raised position desired by securing the pulleys 43 against rotation by 50 means of pawls and ratchet wheels as at 42. It is however desirable to raise the extension ladder to its outermost limits as it is here possible to thoroughly brace the same and thereby materially increase the total 55 strength of the ladder, as will hereinafter be described. The pulleys 43 each carry a cable consisting of a chain section 45 and a rope section 45a. One end of each cable is attached to the extension ladder at a point 60 indicated at 44. The cables, referring to Fig. 1, terminate in chains 45 and pass over the pulleys 43. They then pass up between the rungs of the respective ladder sections and under guide pulleys 46. (See Fig. 3.) 65 They then pass over guide pulleys 47 and

are attached to the upper end of a pair of truss arms 48 which are pivotally secured to the lower end of the extension ladder 2, as shown at 49. Turning movement transmitted to the pulleys 43 causes a pull on the 70 chains and cable which are attached to the truss arms 48. Chains 48 restrain the truss arms 48 against further movement than the right angle position shown. The ladder section 2 is in this manner extended and will 75 finally assume the completely extended position shown in Fig. 1. The cable and the chain 45 here assumes a taut position and as one end is secured at point 44 and the other end to the truss arms 48, it can read- 80 ily be seen that the truss arms will be swung about their pivotal connections into the right angle position shown in Figs. 1, 2 and 3, thereby further increasing the tautness 85 of the cable and chain 45, and to that extent 85 forming a truss which materially increases the total strength of the ladder 2 extended, the important feature of this portion of the structure being the fact that the truss is collapsible and extensible and only assumes 90 a taut and operable position when complete extension of the ladder is accomplished, the cables and the ladder section raised thereby being securely locked against release by the 95 pawls and ratchets 42.

With the ladder raised and extended as shown in Fig. 1, it is possible to employ the poles 29 and thereby raise the ladder to an approximate vertical position against the building or object where the ladder is to be 100 employed. Raising of the ladder beyond the angular position shown in Fig. 1, automatically renders the supporting truck or carriage B inoperative. This is accomplished automatically, due to the fact that a telescopic connection is formed between the ladder and the frame sections 4 and 5 of the carriage. This telescopic connection is clearly shown in Figs. 13 and 14. The pivotal connection between the ladder and the 105 carriage is shown at 3, one section of each pivotal connection 3 carries a rod 50, which passes through a guide member 51 in the upper end of the carriage frame. As the ladder is being swung beyond the angular 110 position shown in Fig. 1 by means of the poles 29, it can be seen that the telescopic connection formed will automatically extend itself as shown in Fig. 13, and that the carriage gradually swings up against the ladder 115 where it may be locked by means of the hocks 52, shown in Fig. 1. It thus becomes inoperative as it is impossible for the carriage to support any weight when the telescopic connection is extended and any danger 120 of the lower end of the ladder slipping or giving away is therefore obviated.

If it is desired to lower the ladder, it is first necessary to swing it into an angular position where the telescopic connection of 125

the carriage reaches its innermost limit and where the pivotal connection 3 can begin to take the weight of the ladder. The ladder is then supported by means of the poles 29, 5 while the pawls and ratchets at 42 are released. The hand cranks 41 are then employed and turned in a direction which permits the ladder sections 2 to return to normal position. The truss arms 48 automatically 10 swing upward into parallelism with the ladder when this takes place and a flat surface will therefore be presented as no projections are desirable. The foot brace frames 21 and 22 are next extended and the ladder swung 15 into the horizontal position shown in Fig. 9. The poles are released by means of the latches 36 and these are run back between the sheaves 34 to a position where the collars 35 engage the fork-shaped brackets 39. The 20 pawls 20' are then brought into engagement with their respective ratchets 20 and the cables and chains 16 and 18 will thus secure the carriage B in vertical position. The chains 12 may then be disconnected and the 25 auxiliary bracing legs raised to the dotted line position shown at 10^a. The ladder may then be rolled over to the truck provided for its reception and may be temporarily supported at its outer ends by a pair of extension legs 60. (See Fig. 1.) The pawls 20' are again released and the carriage B swung up into parallelism with the ladder as shown by dotted lines in Fig. 9, it being here secured 30 by the hooks 52. The foot braces are of course folded into parallelism with the ladder and the temporary supporting legs 60, similarly folded. The ladder is then grasped by the men and slid endwise on the truck where it may be secured in any suitable 35 manner. In removing the ladder it is pulled off endwise and the legs 60 extended to support the outer end. The carriage is then released and swung into vertical position and is locked in this position by swinging the pawl 20' into engagement with its co-operating ratchet gear. The ladder may then be 40 rolled along the ground as it is supported by the carriage to a point where it is to be used and if obstructions of any kind are encountered, such as a gutter or the like, a wedge shaped lock, such as shown in Fig. 21, may 45 be employed to permit the carriage to pass over the obstruction. When the ladder has reached its position, it is only necessary to disengage the pawl 20' and to extend the 50 foot braces 21 and 22. These are then grasped by the men and sufficient weight applied to tilt the ladder into the position shown in Fig. 9. The upper section of the 55 ladder is then extended as previously described and the ladder is finally raised to a vertical position by the poles 29, the carriage of course becoming inoperable when a 60 vertical position is assumed, due to the telescopic action of the connections 50 and 51.

By referring to Fig. 9 it will be seen that the cable 16 is provided with a stop member 16^a. This stop member engages the pulley 17 when the ladder assumes a horizontal position, and it therefore locks the upper or 70 forward end of the ladder from tilting, while the pawl and ratchet on the opposite pulley 19 locks it against tilting in the direction indicated by the dotted lines.

Having thus described my invention, 75 what I claim and desire to secure by Letters Patent is—

1. The combination with a ladder of the character described, of a carriage adapted to support one end thereof, wheels on the carriage, means permitting tilting movement of the ladder with relation to the carriage, means for locking the ladder against tilting movement about the carriage, and means permitting vertical movement of the carriage 80 with relation to the ladder.

2. The combination with a ladder of the character described, of a carriage adapted to support one end thereof, wheels on the carriage, means permitting tilting movement 90 of the ladder with relation to the carriage, means for locking the ladder against tilting movement about the carriage, means permitting vertical movement of the carriage with relation to the ladder, and means for co-operating with the wheels on the carriage for locking the carriage against rolling movement.

3. The combination with a ladder of the character described, of a carriage adapted 100 to support one end thereof, a pivotal connection between the carriage and the ladder permitting tilting movement of the ladder, means for locking the ladder against tilting movement when the carriage 105 assumes a vertical position and the ladder a horizontal position, wheels supporting the carriage, and means co-operating with the wheels for locking the same against rolling movement, said means comprising a pair 110 of auxiliary bracing members for each wheel, said bracing members adapted to be secured to the carriage at their upper ends and to engage the ground at their lower ends.

4. The combination with a ladder of the character described, of a carriage adapted to support one end thereof, a pivotal connection between the carriage and the ladder permitting tilting movement of the ladder, 120 means for locking the ladder against tilting movement when the carriage assumes a vertical position and the ladder a horizontal position, wheels supporting the carriage, means co-operating with the wheels for locking the same against rolling movement, said means comprising a pair of auxiliary bracing members for each wheel, said bracing members adapted to be secured to the carriage 125 at their upper ends and to engage the 130

- ground at their lower ends, and means permitting vertical movement of said members to raise the same out of engagement with the ground, and means for securing the same 5 in vertical position on the carriage.
5. The combination with a ladder of the character described, of a carriage adapted to support one end of the ladder, a pivotal connection between the ladder and the carriage, a telescopic connection permitting vertical movement of the carriage with relation to the ladder, wheels on the carriage, means for securing the carriage against movement on the wheels and means for locking 10 the ladder against tilting movement about its pivotal connection.
6. The combination with a ladder of the character described, of a carriage adapted to support one end of the ladder, a pivotal 20 connection between the ladder and the carriage, a telescopic connection permitting vertical movement of the carriage with relation to the ladder, wheels on the carriage, means for securing the carriage against movement 25 on the wheels, means for locking the ladder against tilting movement about its pivotal connection, said means comprising an endless cable secured to the lower end of the carriage, a chain section in said endless 30 cable, a sprocket over which said chain passes, and means for securing the sprocket against turning movement.
7. The combination with a ladder of the character described consisting of upper and 35 lower telescoping sections, of a support for one end thereof by which the ladder is adapted to be tilted, the lower section of the ladder and support being of such lengths when the ladder is swung beyond the predetermined vertical angular position the 40 support becomes inoperable.
8. The combination with a ladder of the character described consisting of upper and lower telescoping sections, of a carriage 45 adapted to support one end thereof, and a pivotal connection between the support and the ladder permitting tilting movement of the ladder about the support, the lower section of the ladder and carriage being of such 50 lengths that when the ladder is swung beyond a predetermined vertical position, the carriage support is rendered inoperable.
9. The combination with a ladder of the character described consisting of upper and 55 lower telescoping sections, of a carriage adapted to support one end thereof, a pivotal connection between the carriage and the ladder permitting tilting movement of the ladder about the carriage, the lower section 60 of the ladder and carriage being of such lengths that when the ladder is swung beyond a predetermined vertical position, the carriage support is rendered inoperable, and a pair of foot braces secured to the lower end 65 of the ladder and foldable with relation thereto whereby the ladder may be grasped for tilting.
10. The combination with a ladder of the character described, consisting of upper and lower telescoping sections, of a carriage 70 adapted to support one end thereof, a pivotal connection between the carriage and the ladder permitting tilting movement of the ladder about the carriage, a telescoping connection between the pivot and the carriage, 75 the lower section of the ladder being of such length that when the ladder is swung beyond a predetermined vertical position, the telescoping connection between the pivot and the carriage will become extended and render the carriage inoperative, a pair of foot braces secured at the lower end of the ladder and foldable with relation thereto, whereby the ladder may be grasped when it is tilted, and means for locking said foot 80 braces when folded against the ladder.
11. The combination with a ladder of the character described, of an extensible section on the ladder adapted to be raised or lowered with relation thereto, a collapsible 85 truss connecting the extensible section with the main section of the ladder, and means for causing said collapsible truss to assume a taut position when the extensible section 90 is completely extended.
12. A ladder comprising a lower main section and an upper extensible section, a cable attached to one end of the approximate upper end of the extensible section, a truss arm pivotally mounted on the lower end of 100 the extensible section, a guide on one end of said truss arm over which the cable passes, a sprocket wheel on the lower end of the main section of the ladder over which the cable passes, means for securing the end 105 of the cable to one end of the truss arm, and means for exerting a pull on the cable to raise or lower the extensible section.
13. A ladder comprising a main lower section and an extensible upper section, a 110 sprocket gear journaled in the lower end of the main ladder, a truss arm pivotally mounted on the lower end of the extensible section, a cable attached to one end of said truss arm, said cable passing downwardly 115 from the truss arm around the sprocket and then upwardly past the free end of the truss arm, means securing this end of the cable to a point near the upper end of the extensible ladder section, a chain section in the cable 120 passing over the sprocket, and means for imparting a rotary movement to the sprocket in either direction to raise or lower the extensible ladder section.
14. A ladder comprising a main lower section and an extensible upper section, a 125 sprocket gear journaled in the lower end of the main ladder, a truss arm pivotally mounted on the lower end of the extensible section, a cable attached to one end of said 130

- truss arm, said cable passing downwardly from the truss arm around the sprocket and then upwardly past the free end of the truss arm, means securing this end of the cable to 5 a point near the upper end of the extensible ladder section, a chain section in the cable passing over the sprocket, means for imparting a rotary movement to the sprocket in either direction to raise or lower the extensible ladder section, means on the free 10 end of the pivotally mounted truss arm for engaging and guiding the cable, and means for limiting the swinging movement of the truss arm.
- 15 15. The combination with a ladder, of a raising pole therefor, a bracket at the upper end of the ladder through which the pole extends, a universal connection between said bracket and the ladder, means permitting 20 endwise movement of the pole through the bracket, and means on one end of the pole

for locking the pole against endwise movement with relation to the bracket.

16. The combination with a ladder, of a raising pole therefor, a bracket at the upper 25 end of the ladder through which the pole extends, a universal connection between said bracket and the ladder, means permitting endwise movement of the pole through the bracket, and means on one end of the pole 30 for locking the pole against endwise movement with relation to the bracket, said means comprising a latch engageable with one side of the bracket and a collar on the pole engageable with the other side of the bracket. 35

In testimony whereof I have hereunto set my hand in the presence of two subscribing witnesses.
